(57) **CLAIM**

The ornamental design for an integrated sleep mask for hooded garment, as shown and described.

DESCRIPTION

FIG. 1 is right, front perspective view of the integrated sleep mask for hooded garment, in a state of use, showing my new design;

FIG. 2 is a left, front perspective view thereof, in a state of use;

FIG. 3 is a front view thereof;

FIG. 4 is a left front perspective view thereof;

FIG. 5 is a right front perspective view thereof;

FIG. 6 is a rear view thereof;

FIG. 7 is a left, front perspective view thereof, in a second configuration;

FIG. 8 is a right, front perspective view thereof;

FIG. 9 is a rear elevation view thereof;

FIG. 10 is a left side view thereof, in a third configuration;

FIG. 11 is a right side view thereof;

FIG. 12 is a top view thereof, in a fourth configuration;

FIG. 13 is a bottom view thereof;

FIG. 14 is a right side view thereof, in a fifth configuration; and,

FIG. 15 is a left side view thereof.

The broken line illustrating a mannequin illustrate environmental structure that forms no part of the claimed design. The remaining broken lines illustrate portions of the integrated sleep mask for hooded garment and form no part of the claimed design.

1 Claim, 15 Drawing Sheets
